UNITED STATES PATENT OFFICE.

FRANCIS L. FREAS, OF CONSHOHOCKEN, PENNSYLVANIA.

THERMOMETER.

1,316,780.

Specification of Letters Patent. Patented Sept. 23, 1919.

Application filed August 5, 1918. Serial No. 248,247.

To all whom it may concern:

Be it known that I, FRANCIS L. FREAS, of Conshohocken, in the county of Montgomery and State of Pennsylvania, have invented certain new and useful Improvements in Thermometers, whereof the following is a specification, reference being had to the accompanying drawings.

My improvements relate to the so-called insulated thermometers, and may be embodied in a device intended to float in upright position when immersed in liquids, but their use is not restricted to such floating devices.

In the accompanying drawings, Figure I represents an exterior view, in front elevation, of a thermometer embodying my invention; Fig. II, a partial axial section through the lower portion of the thermometer and casing; Fig. III, an interrupted longitudinal section on a plane at right angles to that of Fig. II; and Fig. IV a cross-section on the line IV—IV of Fig. III.

The device comprises the following main elements:

The external casing or insulating member 1 is an elongated cylindrical tube of transparent material, such as thin glass, having preferably a tapered lower portion 2, and terminating at its lower extremity in a rounded end socket 3, whose section may be considered as substantially hemispherical, and whose inner surface should be true and symmetrical. The casing is closed at the upper extremity as shown at 4, and is provided with an eye 5.

The thermometer element is of the usual form, comprising a capillary tube 6, a substantially spherical bulb 7, the exterior surface of the lower half of the bulb being formed in substantial symmetry with the internal surface of the socket 3, and being of such dimensions that said lower half of the bulb may fit snugly within the socket. The capillary tube is bent at an angle a short distance from the bulb, as indicated at 8, and the stem is thus inclined toward the inner surface of the casing, preferably coming into contact therewith near the upper extremity, as shown at 9.

The thermometer element having been arranged in the position shown in the figures, with the bulb 7 seated within the socket 3, I fill the interspace at the lower portion of the casing with granular thermally conducting material, preferably very fine shot, as indicated at 10. Where, as in the instance

shown in the drawings, the lower portion of the casing is tapered, the zone or region occupied by the shot is preferably made to terminate a short distance below the upper extremity of the tapered portion. The shot or granular material is carefully packed, or shaken into a position of complete rest, so that the body of material as a whole shall be practically stable under the conditions of use, and the quantity of material may be determined with reference to the desired buoyancy of the structure, as a whole, in a liquid of given density.

When the bulk has been thus inserted and the body of the granular material properly packed in stable condition, I apply a belt 11 of material which is capable of being introduced in a plastic condition, but which will harden, and remain strongly adhesive to the glass of the casing and of the thermometer element. If the material of the belt 11 is of such character as to be rendered plastic by heat, (such as sealing wax, for instance) it should have a softening-point not substantially lower than the highest temperature to which the thermometer would be subjected under normal conditions of use.

When the belt of adhesive material has been applied and hardened in adhesive relation to the respective glass surfaces, the thermometer element will be retained with great stability in position with its upper end preferably in light contact with the surface of the casing, by the combined effect of the bulb fitting within the socket 3, the extended support afforded by the body of granular material 10, and the belt of adhesive material 11. In order, however, further to enhance the stability of the capillary tube, particularly at its upper portion which is remote from the embedded bulb and lower portion of the stem, I employ a scale element, formed preferably of paper having a substantial amount of stiffness, which is disposed in the form of a cylinder 14 fitting closely within the bore of the casing, and which is inserted behind the capillary tube in such manner that a longitudinal depression, or trough, 15, is formed in the side of the paper cylinder, corresponding to the tube, the paper thus exerting tension against the tube throughout the greater portion of its length.

The graduations indicating the divisions of the thermometer scale, are preferably imprinted upon the paper along the trough, and the thermometer figures are preferably

arranged in longitudinal bands on each side of the graduations as shown. When the paper cylinder has been inserted to the proper depth (which is, of course, determined by the known relation of the expandable material within the bulb and capillary tube to the indicated scale temperatures), the paper cylinder is preferably secured in position by adhesive material applied at its 10 upper region, so as to be held permanently in place, such securing being aided by the frictional contact between the paper cylinder and the interior surface of the casing, due to the pressure occasioned by forcing the 15 paper cylinder behind the capillary tube. Subsequently, of course, the upper end of the casing is closed, as shown.

I am aware that it is not new to form insulated thermometers by making the glass 20 of the thermometer bulb integral with the glass of the lower extremity of the casing, but such devices are difficult and expensive to make, and are obviously structurally different from the device embodying my invention.

I am also aware that the use of shot for weighting purposes in hydrometers and similar instruments is not new.

Having thus described my invention, I 30 claim:

1. In a thermometer, the combination of a closed casing having, at its lower extremity, a socket with a substantially symmetrical internal surface; a thermometer element in said casing having a bulb adapted to fit within said socket and an upward extending capillary tube; a substantially stable granular packing in said casing confined to the lower portion thereof and in 35 contact with the lower portion of said thermometer element; and a belt of adhesive material above said packing securing the same in place in said casing.

2. The combination of; a closed cylindri-

cal casing having, at its lower extremity, a 45 socket with a substantially symmetrical internal surface; a thermometer element arranged within said casing, having a bulb adapted to fit within the socket of the casing, and having a capillary tube bent at its lower 50 portion; a substantially stable body of granular thermally conducting material, arranged in contact with the lower portion of said thermometer element; a belt of adhesive material arranged in contact with the upper 55 surface of said granular body and secured to the interior surface of the casing and exterior surface of the capillary tube; and a scale member arranged in proper relation to the thermometer element, substantially as 60 set forth.

3. The combination of; a closed cylindrical casing having, at its lower extremity, a socket with a substantially symmetrical internal surface; a thermometer element arranged within said casing, having a bulb adapted to fit within the socket of the casing and having a capillary tube bent at its lower portion; a substantially stable body of granular thermally conducting material, arranged in contact with the lower portion of said thermometer element; a belt of adhesive material arranged in contact with the upper surface of said granular body and secured to the interior surface of the casing 70 and exterior surface of the capillary tube; and a scale member of relatively stiff pliable material, disposed in cylindrical form, and having a longitudinal trough adapted to receive the capillary tube, in tensional relation thereto, substantially as set forth.

In testimony whereof, I have hereunto signed my name, at Philadelphia, Pennsylvania, this first day of August, 1918.

FRANCIS L. FREAS.
